UNITED STATES PATENT OFFICE

2,503,596

METAL STRUCTURE

Francis I. Rataiczak, Dayton, Ohio, assignor to
General Motors Corporation, Dayton, Ohio, a
corporation of Delaware

Application May 19, 1944, Serial No. 536,229

7 Claims. (Cl. 89—1)

1

This invention relates to metal structure and more particularly to an improved machine gun construction.

One object of this invention is to provide a low cost machine gun capable of firing high powered 60-caliber ammunition.

Another object of this invention is to improve upon the receiver construction so as to make a strong light weight receiver suitable for mass production.

Further objects and advantages of the present invention will be apparent from the following description, reference being had to the accompanying drawings, wherein a preferred form of the present invention is clearly shown.

In the drawings:

Fig. 1 is a side elevational view of a gun embodying my invention;

Fig. 2 is a side elevational view similar to Fig. 1 but showing the breech cover raised;

Fig. 3 is a top view of the gun;

Fig. 4 is a plan view showing the construction of the receiver;

Fig. 5 is an elevational view of the receiver;

Fig. 6 is a sectional view taken on line 6—6 of Fig. 5;

Fig. 7 is a sectional view taken on line 7—7 of Fig. 5;

Fig. 8 is a sectional view taken on line 8—8 of Fig. 5;

Fig. 9 is a sectional view taken on line 9—9 of Fig. 5;

Fig. 10 is a sectional view taken on line 10—10 of Fig. 5;

Fig. 11 is a front end elevational view of the receiver shown in Figs. 4 and 5.

Referring now to Figs. 1, 2 and 3 of the drawing, reference numerals 50 and 52 designate the breech housing and barrel respectively of a 60-caliber rapid fire machine gun. Reference numeral 54 designates generally the cover for the breech housing which is pivotally secured to the breech housing at 56. A belt feed mechanism 58 is removably secured to the cover member 54. The feedway 60 which is secured to the breech housing or receiver 50 cooperates with the belt feed mechanism 58 to direct the feed belt and the cartridges carried thereby into the breech housing 50.

Reference numeral 64 designates generally an adapter which is used for mounting the gun and which incorporates a standard buffer arrangement, the details of which form no part of my invention and will not be described in detail. The cover 54 may be latched in its downward position by the cover latch (not shown) which engages the cover latch strike 68 carried by the breech housing 50. The latch is operated by means of the handle 70 (Figs. 1, 2 and 3) which is arranged as shown.

2

The breech housing 50 (Figs. 4—11) is made up in a novel manner in that it comprises a pair of stamped sheet metal elements 130 and 132 and a pair of end pieces 136 and 140 as best shown in Figs. 4 through 11. These two stamped sheet metal elements are individually formed in the required shape, and are thereafter fitted within one another as shown and are riveted together by means of a plurality of rivets such as the 10 rivets 134 which are primarily used to hold the parts in proper assembled relationship during subsequent manufacturing operations on the breech housing or receiver assembly. Figs. 4 through 11 show the parts in an intermediate 15 stage of completion. The end piece 136 is secured to the stampings by means of suitable screws 138 arranged as shown in Figs. 5 and 6. A relatively heavy front end element 140 is riveted to the stamping 130 as shown in Fig. 10. After 20 the various parts which make up the breech or receiver housing 50 have all been riveted or screwed together, the assembly is hydrogen brazed, whereby all of the parts shown in Figs. 4 through 11 become the equivalent of one integral piece. By virtue of the above described arrangement, the amount of material required in the manufacture of the breech housing or receiver has been very materially reduced, and the weight of the breech housing or receiver has likewise 25 been very materially reduced. Thus, with this type of construction it is possible to make the receiver strong without making it bulky. Another advantage of the arrangement shown in Figs. 4—11 is that the time required in forming the various guide channels and the like has been 30 materially reduced since the need for hogging out a large amount of metal from a large forging or piece of bar stock has been eliminated. Subsequent to the hydrogen brazing operation, many 35 or all of the heads of the rivets 134 may be ground off so as to provide smooth surfaces.

The relatively heavy end pieces 136 and 140 serve to reinforce the lighter weight stampings at the ends thereof and also provide rigid mounting members which may be machined the same 40 as if the entire breech housing were made from a large piece of heavy bar stock.

As best shown in Figs. 7 through 11, the inner stamping 132 is provided with opposed ledges 142 45 which serve to guide the bolt assembly generally designated by the reference numeral 150. The rear end piece 136 is suitably machined so as to serve as the housing for the bolt buffer mechanism. Since the bolt buffer mechanism which 50 comprises a plurality of concentric springs is of standard construction and since the details thereof of form no part of this invention, other than the manner in which the element 136 is formed and held in place, the bolt buffer mechanism will not 55 be described in greater detail.

The ejected shells leave the breech housing 50 through the bottom opening 199.

The bolt (not shown) has an upwardly extending lug 209 which is visible in Figs. 1 and 2. At the back of the cover 54 is a hand engaging element 224 for hand cocking. The housing 252 of the feed rack support projects from opposite sides of the cover 54 as shown in Fig. 3. The guide plate 286 carried by the cover 54 helps to guide the cartridge into place.

It will be noted that the cover 54 is a sheet metal stamping. By virtue of the shape of the cover which comprises both flat and rounded portions, the cover is inherently strong, yet light weight and inexpensive to manufacture.

While the form of embodiment of the invention as herein disclosed constitutes a preferred form, it is to be understood that other forms might be adopted, as may come within the scope of the claims which follow.

What is claimed is as follows:

1. A receiver for use in a rapid fire machine gun comprising in combination, a pair of stamped sheet metal elements forming the main body of said receiver, one of said elements comprising an outer element of substantially semicircular cross section, the other of said elements comprising an inner member substantially U-shaped in section with the upper ends of the arms of the U offset outwardly so as to engage the outer semicircular member and so as to provide substantially horizontal surfaces for guiding a reciprocating breech bolt.

2. In a rapid fire machine gun, a receiver for guiding the breech bolt of the gun comprising in combination a pair of stamped sheet metal elements, at least one of which is formed to provide a breech bolt guide channel, and the other of which serves to reinforce said breech bolt guide channel and forming therebetween a pair of longitudinally extending air passages.

3. A guide including an outer shell having a hollow substantially semi-cylindrical portion, an inner sheet metal member having a lower U-shaped portion, the bottom of the U-shaped portion contacting the bottom of the outer shell for the greater portion of its length, said inner sheet metal member having its opposite sides above the lower U-shaped portion extending horizontally outwardly until they contact the outer shell to form guide ledges, said inner member and the outer shell being fastened together at their contacting bottom portions and at the contacting surfaces of the outermost parts of the inner member and the outer shell.

4. A guide including an outer shell having a hollow substantially semi-cylindrical portion, an inner sheet metal member having a lower U-shaped portion, the bottom of the U-shaped portion contacting the bottom of the outer shell for the greater portion of its length, said inner sheet metal member having its opposite sides above the lower U-shaped portion extending horizontally outwardly until they contact the outer shell to form guide ledges, said inner member having flanges at the outer edges of the guide ledges in contact with inner surfaces of the outer shell, said flanges being fastened to said outer shell.

5. A guide comprising an inner and an outer sheet metal element, said inner sheet metal element having a lower U-shaped portion, the bottom of the U-shaped portion contacting the outer

sheet metal element for a substantial portion of its length, said inner sheet metal element having its opposite sides above the lower U-shaped portion extending horizontally outwardly until they contact the outer sheet metal element to form guide ledges, said inner and outer sheet metal elements being fastened together at their contacting bottom portions and at the contacting portions of the outermost parts of the inner and outer sheet metal elements.

6. A receiver comprising inner and outer sheet metal elements, said inner sheet metal element having a lower U-shaped portion contacting the outer sheet metal element for a substantial portion of its length, said inner sheet metal element having those portions of its opposite sides above the lower U-shaped portion extending horizontally outwardly until they contact the outer sheet metal element to form guide ledges, said outer sheets metal element extending around the bottom and side portions of the inner sheet metal element, said inner and outer sheet metal elements being fastened together at their contacting bottom portions and at the contacting portions of the outermost parts of the inner and outer sheet metal elements, and reinforcing end elements located within the end portions of the inner and outer elements and being tightly fastened to both the inner and outer elements to reinforce them and complete the receiver.

7. A guide comprising an inner and an outer sheet metal element, said inner sheet metal element having a lower U-shaped portion, the bottom of the U-shaped portion contacting the outer sheet metal element, said inner sheet metal element having its opposite sides above the lower U-shaped portion extending horizontally outwardly until they contact the outer sheet metal element to form guide ledges, a portion of the bottom of the inner element being open and having at the sides of said open portion substantially vertical walls extending downwardly from said guide ledges, said outer sheet metal element extending into contact with said substantially vertical walls, said inner and outer elements being fastened together at their contacting portions.

FRANCIS I. RATAICZAK.

Certificate of Correction

April 11, 1950

FRANCIS I. RATAICZAK

It is hereby certified that error appears in the printed specification of the above numbered patent requiring correction as follows:

Column 1, line 60, after the word and period "shown." insert the following paragraph:

A retaining collar 112 is screwed onto the front end of the breech housing or receiver 50 in the manner shown and holds the barrel support in fixed relationship relative to the breech housing or receiver 50.;

and that the said Letters Patent should be read with this correction therein that the same may conform to the record of the case in the Patent Office.

Signed and sealed this 11th day of July, A. D. 1950.
